UNITED STATES PATENT OFFICE.

WILLIAM J. MENZIES, OF ST. HELEN'S, COUNTY OF LANCASTER, ENGLAND.

MANUFACTURE AND PREPARATION OF POTASH SOAP.

SPECIFICATION forming part of Letters Patent No. 286,049, dated October 2, 1883.

Application filed August 23, 1883. (No specimens.)

To all whom it may concern:

Be it known that I, WILLIAM JONES MENZIES, of St. Helen's, county of Lancaster, England, have invented a certain new and useful improvement in the manufacture and preparation of potash soaps for household purposes, and in the packages and methods for transporting the same, of which the following is a specification.

10 Hitherto the potash soaps of commerce have been unfit for laundry, toilet, and other household and general purposes, for three reasons: first, that as a matter of fact they have been all of a strongly alkaline and corrosive nature, owing to the impure potash from which they have been made; secondly, they have been largely made from fish-oil and strong-smelling seed-oil, which made the soap unpleasant to use and imparted a strong smell to any article 15 which was washed with it; thirdly, the article has hitherto been packed in large kegs or packages, a small quantity out of which could not be conveniently retailed or sold at stores for household use, (as in the case of hard soda 20 or soap,) unless a can or jar was brought to receive it, owing to the soft nature of the soap.

Now, I have discovered that the first objection to potash soap for household use is entirely obviated by making the soap with caustic potash instead of wood-ashes, (which is now 25 sold as a commercial article of considerable degree of purity,) and thus enabling a neutral or closely approaching to a neutral potash soap to be produced, which, with the old wood-ashes or carbonate of potash, was unobtainable, as pointed out in Letters Patent of the

United States No. 254,832, already granted to me.

The second objection can be overcome by using sweet-smelling oils, such as palm-oil; or 40 the soap can be perfumed with essential oils, in the same manner as hard soap, which has never before been done.

The third objection is obviated by putting up for household use in small and convenient-sized metallic, glass, or earthenware, wood, or paper packages, the neutral potash soap, either made with sweet oils or perfumed, thus enabling a potash soap to come into general use for household and even toilet purposes, and for which purposes, when the difficulties I have pointed out are obviated in the manner I have described, is far superior to soda soap.

What I claim, and desire to secure by Letters Patent, is—

1. A potash soap made with sweet oils, without an excess of alkali, and perfume added thereto, substantially as and for the purpose described.

2. A potash soap made with sweet oils without excess of alkali, either with or without perfume, and packed in convenient-sized packages of glass, earthenware, metal, wood, or paper, substantially as and for the purpose 65 described.

In witness whereof I have hereunto set my hand.

WILLIAM J. MENZIES.

Witnesses:

GEO. H. SONNEBORN,
O. B. MORRIS.
